UNITED STATES PATENT OFFICE.

LA FAYETTE JAKE RICHARDSON, OF COLUMBUS, MISSISSIPPI, ASSIGNOR OF ONE-HALF
TO J. Q. STAPLES, OF STEWART, MISSISSIPPI.

CAR-SEAL.

1,163,857.

Specification of Letters Patent. Patented Dec. 14, 1915.

Application filed April 3, 1915. Serial No. 19,053.

To all whom it may concern:

Be it known that I, LA FAYETTE JAKE RICHARDSON, a citizen of the United States, residing in Columbus, in the county of 5 Lowndes and State of Mississippi, have invented a new and useful Car-Seal, of which the following is a specification.

My invention relates to improvements in car seals, wherein a blank, of the configuration shown in the accompanying drawing, 10 can have each integral part successively so bent, as to form a lock incapable of being opened without destructive mutilation of the seal terminating its utility.

15 The objects of my invention are: first, to produce a blank, the successive folds of whose integral parts will form a secure seal to a freight car in transit; second, to produce an inexpensive blank that will attain 20 within itself by easy manual manipulation an effective seal; and third, to secure these results with structural simplicity and economy. I attain these ends by means of the seal shown in different attitudes in the accompanying drawing, wherein—

Figure 1 represents a plan of the seal blank as manufactured; Fig. 2 represents a plan view thereof, after the first fold on the lines B—B of Fig. 1; Fig. 3 represents a 30 plan view of the blank after the second fold, on the lines A—A of Fig. 1; Fig. 4 represents a plan view of the blank after two more folds are made thereof respectively on the lines C and D of Fig. 1; and Fig. 5 is a 35 side elevation, partly in section, on the line 5—5 of Fig. 4.

The same designations indicate corresponding parts in all the views.

The blank has at one end of the sealing 40 portion a long arm 1, slotted at 2 and pointed at 3, as shown, and a short arm 4 at the other end thereof. Projecting rectangularly from the arm 1, is an extension 5 parallel therewith, adapted to be bent on the line 45 A—A, and a downward extension 7, also parallel therewith, adapted to be bent on the lines B—B. The extension 7 has an integral prolongation 6 thereof adapted to

be folded on the line C. The short arm 4 also is adapted to be folded on line D, and 50 its end 9 is bent after the seal has been adjusted. The part 6 projects from extension 7, said extension 7 terminating in a part 8 which is adapted to be folded on dotted lines to produce the parts 8¹ and 8^a by which 55 the seal is secured, as shown in Figs. 2 and 3, and rests in the bed a.

The operation of my blank is as follows: First, the part 8 is bent upwardly on the dotted lines; second, the part 7 is bent on 60 the lines B—B to superimpose arm 1; third, the part 5 is folded on lines A—A to superpose part 7; fourth, the prolongation 6 is folded on line C to superpose part 5; fifth, the short arm 4 is bent on line D, to superpose part 6; sixth, the arm 1 is then bent 65 to form a loop, and the pointed end 3 is passed between the upper surface of the inner part of arm 1 and the under surface of part 7, until the slot 2 engages the parts 70 8¹ and 8^a; seventh, the short arm 4 is then bent, in this manner forming a reliable, economical seal to lock the door of a freight car.

Having thus fully described my invention, 75 what I claim is:

As a new article of manufacture, a blank capable of transformation into a car seal, consisting of a long and short arm antipodally arranged from the central body; lateral 80 upward and downward extensions from the central body adapted successively to be folded upon each other; the downward extension provided with a locking part, normally resting in a bed of the central body, and having 85 portions bent at an angle to receive the slot of the long arm of the blank; and the short arm, folding upon the upward extension; the whole coöperating as and for the purpose described. 90

Witness my signature this March the 31st, 1915.

L. F. JAKE RICHARDSON.
